UNITED STATES PATENT OFFICE.

SAMUEL E. DIESCHER AND AUGUST P. DIESCHER, OF PITTSBURGH, PENNSYLVANIA,
ASSIGNORS TO S. DIESCHER & SONS, OF PITTSBURGH, PENNSYLVANIA, A PARTNERSHIP
CONSISTING OF SAMUEL E. DIESCHER AND AUGUST P. DIESCHER.

FEEDING SHEETS.

Application filed July 16, 1923. Serial No. 651,980.

The invention described herein relates to certain improvements in mechanism for feeding sheets one by one from a pile or pack, the improvement being especially 5 adapted to the feeding of metal sheets to tin pots.

In the manufacture of tinned sheets, the iron or steel blades, after being rolled to gauge, are subjected to what is known as 10 white pickling for the removal of all scale or other foreign matter, and to produce surfaces to which the tin will adhere. After pickling, the sheets are washed to remove all acid from their surface and are kept submerged in water until fed into the tinning machine to prevent oxidation. In washing, 15 a large number of sheets are arranged on edge and so supported that the sheets may be slightly separated when moved up and down in the water. In the washing all air is driven from between the sheets with the result that when sheets are placed in packs the wet surfaces of adjoining sheets will adhere so that great care must be taken, even 20 when sheets are fed to the tinning machine by hand, to avoid feeding two sheets at the same time. It is largely this adherence of adjoining sheets that has rendered automatic feeding of sheets commercially impracticable. It is characteristic of mechanisms heretofore suggested for feeding sheets, that the top or outer sheet of the pack was slid along the next lower or adjoining sheet, or the entire sheet was lifted away 25 from the pile. In neither of these methods was any break of the bond between the top or outer sheet and the next sheet, due to suction, in any way destroyed, and it frequently happened that one or more sheets would be 30 moved with the top, or outer sheet.

The invention described herein has for its object the vertical movement of one end or edge of a top sheet away from the adjacent sheet, such initial movement being followed 45 by a sliding movement of the top, or outer sheet, and progressive separation of the underlying or next adjoining sheet. The invention is hereinafter more fully described and claimed.

50 In the accompanying drawings forming a part of this specification, Fig. 1 is a side elevation of a sheet feeding mechanism embodying the improvements claimed herein; Fig. 2 is a sectional elevation of the same;

Figs. 3 and 4 are transverse sections in a 55 plane respectively indicated by the lines III—III, and IV—IV, Fig. 2; Fig. 5 is a plan view; Fig. 5^a is a sectional plan view of the machine; Fig. 5^b is a plan view showing a preferred arrangement of suckers on the 60 drum; Fig. 6 is a sectional view on an enlarged scale showing parts directly operative on the sheets; Fig. 7 is a sectional detail view, the plane of section being indicated by the line VII—VII, Fig. 2; Fig. 8 is a top 65 plan view of the abutment for determining the position of a pile of sheets in the supporting platen; Figs. 9 and 10 are sectional elevations of the abutment, the planes of section being indicated respectively by the lines 70 IX—IX and X—X, Fig. 8; Fig. 11 is a sectional elevation of the overflow for the tank; Fig. 12 is a detail view illustrating an adjustment of the fingers employed for guiding sheets as they are moved one by one from 75 the pile to the feed rolls; Fig. 13 is a sectional view on a plane indicated by the line XIII—XIII, Fig. 12; Fig. 14 is a detail view illustrating a modification of the manner of employing the guide fingers; Figs. 15, 80 15^a and 16 are sectional detail views showing a cup or sucker entering the liquid in which a pile of sheets are submerged and also showing the leakage perforation; also showing the manner of regulating the degree of 85 vacuum in the cups by regulating the level of water in the tank; in Fig. 16 a cup or sucker is shown having its edge roughened or notched for the circulation of air to the cup; Figs. 17, 18 and 19 are diagrammatic 90 views illustrating successive steps in lifting and advancing a sheet; Fig. 20 is a sectional elevation illustrating a modification of the lifting and feeding drum; Fig. 21 is a transverse section of the drum shown in Fig. 20; and Fig. 22 is a view similar to Fig. 21 illustrating a further modification of the lifting 95 and feeding drum.

In the practice of the invention, a vertically movable platen 1 is arranged in a tank 100 2 located when the mechanism is employed for feeding sheets to a tinning machine, immediately in front of the latter. In the construction shown herein the platen is provided with side plates 3 suspended from a shaft 105 4 which is extended through guide blocks 5 and lifting bars 6. The blocks 5 are arranged in vertical slots 7 in side frames 8 of

the machine. The upper ends of the lifting bars 6 are connected to one end of levers 9 pivotally mounted on posts 10 and having counterweights 11 adjustably mounted on 5 the portions extending beyond the posts so as to exert an upward pull on the lifting bars and platen. A shaft 12 mounted on suitable bearings below the tank is provided with arms 13 having weights 14 adjustably mounted thereon and to the shaft is secured treadles 15 through which pass a bar 16 adapted to be connected to the lower ends of the lifting bars by links 17, so that by depressing the treadle the platen will be 10 moved down to permit of the placing of a pile of sheets in position to be fed to the tin pot as hereinafter described. The weights 11 and 14 are employed for counterbalancing the platen and the parts movable therewith. The upward movement of the platen and the sheets carried thereby is effected by means automatically variable as regards lifting power, as sheets are removed from the platen. As shown in Fig. 1 rods 18 have 15 their upper ends pivotally connected to the levers 9 preferably at points midway between the fulcrum posts 10 and their connections to the lifting bars 6, and to these suspended rods are connected one end of arms 19 and 20; the opposite ends of the arms are pivotally connected, one (19) to the standards 8 and the other (20) to the lifting bars 6. These arms pass through yokes 21, arms 20 bearing against the lower 20 ends of the yokes, while the upper arms 19 bear against movable blocks 22 arranged in said yokes, and between the block and adjustable cross heads 23 are interposed springs 24 as shown in Figs. 2 and 7. As in this 25 construction the ends of the arms 19 connected to standards 8 are stationary, the springs will exert an upward pull on the arms 20 and through these arms on the lifting bars 6 and platen 1. For operation, 30 the tension of the springs 24 will be so adjusted as to cause the top sheet of a pile arranged on the platen to bear with a certain predetermined pressure on a plurality of discs arranged on a shaft 25 which has 35 its ends mounted in roller bearing boxes 26 adjustably mounted in slots in the sides 8 of the machine, as shown in Fig. 3. As is well known, the force exerted by a spring under compression will vary proportional 40 to the expansion of the spring, hence in the construction shown, the removal of a sheet from the top of a pile will permit of an elongation of the springs proportional to the thickness of the sheet and the force exerted by the springs 24 will be proportionally 45 reduced, hence the removal of sheets will not vary the pressure of the discs 25 on a pile.

As shown in Figs. 1, 2, 3 and 5, the upward pull of the springs 24 on the lifting bars 6

can be varied by adjusting the tension of the springs or by shifting the yokes along the arms 19 and 20. This can be conveniently effected by rods 24^a having threaded portions engaging threaded openings in blocks 24^b movably mounted in the yokes. In order to ensure uniform adjustment of the yokes, a sprocket chain 24^c is passed around sprocket wheels 24^d on the respective rods 24^a. 70 75

The progressive movements of a sheet up from a pile and transversely thereof, is effected by a plurality of devices adapted to detachably engage top sheet of a pile, and having such movements that the front edge 80 of the sheet will be pulled upwardly, the sheet moved edgewise and during such edgewise or horizontal movement successive portions of the sheet are moved up from the pile. In the construction shown herein the devices employed for engaging the sheet consist of cups 27 formed of flexible resilient material as rubber, and having cavities in the faces and adapted to contact with the sheet, so that when the cups or suckers are pressed against the surfaces of a sheet, air or liquid will be forced partially or entirely from these cavities and the cups or suckers will adhere to the sheet, (see Fig. 6). The cups or suckers are secured to the periphery of a drum 27^a in rows peripherally of the drum, but preferably with the suckers in one row longitudinally of the drum in staggered relation to those in adjoining rows, as shown in Fig. 5 or as shown in Fig. 5^b. The journals of this drum are mounted in boxes 28, slidably mounted in suitable bearings 29 on the frame of the machine. The drum is so arranged in the rear of the holding discs 25 and in such relation to the top sheet of the pile that the cups or suckers will be flattened and the edges thereof will bear uniformly against the surface of the sheet when the axes of the cups coincide with a vertical plane coincident with the axis of 100 105 the drum. And further, the drum has such a position relative horizontally to the front end of the pile when in position on the platen, that the engagement of the cups or suckers with the sheet will be completed in 110 115 the manner above stated a short distance from the front end of the sheet as shown in Figure 17. While the pile of sheets may be placed directly on the platen, it is preferred to place it on a slide adapted to be shifted on the platen until the front end of the pile bears against an abutment so located that the front end of the pile will be a short distance in front of a vertical plane coincident with the axis of the 120 125 drum when in normal position. Although the abutment can be stationary, it is preferable to rotate same since such rotary surface offers less resistance to the sheets being slid along its surfaces. This rotating abut- 130

ment is preferably constructed for reasons hereinafter stated in the form of a head 30 (see Figures 8, 9, and 10,) secured on the upper end of a vertical shaft 31 which extends down through a tubular column 32, projecting upwardly through the bottom of the tank 2 and is preferably rotated by suitable gearing indicated at 33, as when rotated there will be less resistance to the movement of the sheet when lifted as herein-after described. As shown in Figure 9, the column extends above the lower edge of a curtain 34 on the head, thereby forming an air pocket which will prevent water from flowing up to the open upper end of the column. A flange 35 is formed on the column and is provided with posts 36. The posts are so arranged with reference to the head so that a small portion of the periphery of the head will project beyond the posts and contact with the front ends of the sheets in the pile. The purpose of the posts is to prevent the sheets assuming an angular position relative to the direction in which they are to be fed.

When a line of suckers is brought by the rotation of the drum to the position where they grip the sheet, as above stated, they will tend to move the top sheet forward but as such movement will be prevented by the abutment or head, the drum will be moved a short distance to the left, see Figs. 2, 6 and 17, its journals being mounted in movable boxes 28 yieldingly held in normal position by springs 37 on the rods 38 connected to the boxes 28, said springs bearing at one end against the guide frame 29 and at their opposite ends against collars on the rods 38. In order to ensure equal movements of the ends of the drum 27^a, sleeves 39 fitting loosely on the journals of the drum are connected to the ends of the legs of a U-shape frame 40 which is rotatably mounted on a shaft 41 having its ends secured in the sides of the frame of the machine.

As hereinbefore stated, a line of suckers will grip the top sheet as they reach a vertical plane passing through the axis of the drum and are therefore in their lowest positions and hence when the drum moves back, or rolls to the left, on the sheet, the suckers gripping the sheet will begin their upward movement and will pull the front end of the sheet above the wall of the head. As soon as the sheet is moved above the head the drum will be swung forward or to the right as shown in Figs. 2, 6, 18 and 19 by the springs 37 and the continued rotation of the drum will move the sheet between guides whereby the sheet is directed to the feed rollers 42 or other means whereby the sheets can be moved onward. The lower guide bars 43 are supported in any suitable manner preferably by securing their lower ends to the posts 36 on flange 35 of the tubular column 32. The

upper guides consist of a plurality of pairs of curved and rearwardly projecting fingers 44, and forwardly projecting fingers 44^a; each pair of fingers 44 is secured to a bar 45 and a finger 44^a; one for each pair 44 is also secured to said bar. In operation the fingers 44 extend between adjacent peripheral rows of suckers and rest on the pile of sheets. The upper ends of the bars 45 extend up between plates 46 which extend across the machine and are supported on the sides of the frame of the machine, and the horizontal position of the fingers relative to the drums are determined by swinging the bars on a shaft 48, passing through vertical slots on the bars 45 by set screws 47 passing through the plates 46 and bearing against the upper ends of the bars.

As before stated, the fingers 44 extend under the drum 27^a and between the peripheral rows of suckers, and are made of a width slightly less than the distance the suckers project from the drum. The curvature of the fingers is such that as the sheet is moved longitudinally upward by the suckers; the edges of the fingers will exert a progressively increasing pressure on the sheets in a direction to release them from the suckers. In order to facilitate the separation of the sheets from the suckers, provision is made for a gradual reduction of the vacuum under the suckers, either by roughening or by cutting small notches 49 in the edges of the suckers 27 or forming minute holes 50 through the walls thereof as shown in Figs. 15 and 16. By properly proportioning the sizes of the notches or holes, the adherence of the sheets may be made very slight or entirely destroyed by the time the suckers have reached the plane when the release of the sheets is desired. As will be seen by reference to Figs. 15, 15^a, and 16 the degree of adhesion of the cup to sheets when submerged in water, can be regulated by varying the level of the water in the tank. As for example, in Fig. 16 the level of the water is such that when the cups are moved to position to adhere to the sheet, a considerable quantity of air will be entrapped in the cup and the adherence of the cup will be reduced in direct proportion to the volume of air entrapped. In Fig. 15 the level of the water in the tank is such as to remove all air and the adherence of the cups will reach a maximum value.

It is preferred that the suckers should be constructed and connected to the drum so that the sheet may be moved short distances from the drum while engaged or gripped by the suckers. As for example, the suckers can be made of rubber and provided with rubber stems 27^b engaged by thimbles 27^c screwing into threaded holes formed in the periphery of the drum, as shown in Fig. 6. The construction of the suckers will permit

of bending the sheets transversely by so setting the fingers 44 that the edges contacting with the sheets will be in different positions relative to the arcs of circles in which the suckers move while engaging the sheets, as shown in Figs. 12 and 13. As for example, if the outside pairs *a* of fingers have a certain position, and the pairs *b* be adjusted so that the edges will be a little further from the drum, the sheet will be bent transversely, and such flexure will, in case a sheet should adhere to the underside of the sheet being fed, effect the release of the under sheet. Such release of an adhering sheet may be effected by imparting movements to adjoining pairs of fingers, except the outside pairs which would be held in normal position. The pairs of fingers adjacent to the outer pair would be reciprocated back and forth relative to normal position a short distance, e. g., one-eighth of an inch, and the remaining pairs would be reciprocated a little greater distance, e. g., one-fourth of an inch. By this reciprocation the top sheet would be curved from side to side, first in one direction and then in the opposite direction, as shown in Fig. 13. These movements of the top sheet can be effected by substituting rotating eccentrics 51 for the setscrews 47 as shown in Fig. 14.

In order that the relative peripheral speeds of the drum 27^a and the feed rollers 45 should be maintained, it is preferred that the shaft 52 which is provided with a worm 53 engaging a worm-wheel on the journal of the drum, should be provided with a beveled pinion engaging a correspondingly shaped pinion on the shaft of one of the feed rollers.

In order to assist in the separation of the top sheet from the underlying sheet, it is preferred to direct jets of water under high pressure against the front ends of the sheets. To this end brackets consisting of a base plate 55 and nozzles 56 are adjustably secured to the front wall of the tank 1 so that the nozzles project rearwardly to points closely adjacent to the front ends of the pile when in position on the platen. It is preferred that the discharge openings of the nozzles should be elongated vertically. The employment of the jets of water against the edges of the sheets will have a separating action and when the front ends of the top sheet are lifted water will be forced backwardly between the top and next adjacent sheet and the former, when removed longitudinally, will move on a film of water.

When employing this mechanism for feeding sheets to tinning machines, the piles of sheets are kept submerged in the water in the tank, the water being supplied thereto either through the nozzles 56 or in any other suitable manner. In order to maintain the proper level of water in the tank, a suitable

overflow is employed, such for example as that shown in Figs. 4 and 11. A pipe 57 extends up through the bottom of the tank and is connected to a shell 58, having its upper portion enlarged and internally threaded below the enlargement for engagement with the externally threaded portion of nipple 59, such construction permitting of the vertical adjustment of the nipple. The enlarged upper portion of the shell is provided with inlet ports 60 communicating with the tank. The nipple 59 is so constructed at a point above the level of the ports 60 as to permit the flow of water from the shell into and down through the nipple, shell, and waste pipe 57. In the construction shown, the upper end of the nipple is constructed to be engaged by a tool 61 to turn the nipple and change the position of ports 60 in the nipple relative to the bottom of the tank. In order to prevent to a great extent at least, the accumulation of dirt at the bottom of the tank, it is preferred to connect the ports 60 in the shell to pipes 63 extending down to points adjacent to the bottom of the tank.

In lieu of employing cups or suckers adapted to adhere to the sheets by the latter displacement of fluid in the cups, as hereinbefore described, the suckers may be formed with passages formed axially of their stems and communicating with the interior of the drum, as shown in Figs. 20 and 21. The drum is provided with hollow journals 64, which are adapted to be mounted in the boxes 28. Through the journals is passed a stationary shaft 65 having an axial passage 66 and radial ports 67 extending therefrom. A U-shaped box 68 is so arranged within the drum as to enclose the ported portion of the shaft 65 and the edges of its open side bear on the inner surface of the drum. The box is keyed to the shaft 65 to prevent its being moved by the drum in its rotation. The passage in the shaft is connected to a suitable means for maintaining a sufficient vacuum within the box to ensure the adherence of the cups or suckers to the sheet. The box is so arranged that when a line of suckers reaches a position where the axes of the suckers coincide with a vertical plane coincident with the axis of the drum, the axial passages of the discs will pass within the box and the cups caused to adhere to the sheets. The opposite wall of the box is so located that the axial passages of the cups will pass out of the box when the cups have reached points at which the sheet should be released.

In lieu of effecting the initial vertical movement of the front end of the top sheet by a backward movement of the drum carrying the suckers as hereinbefore described, such initial vertical movement of the sheet can be effected by causing the suckers to

move radially immediately after they have taken a grip on the top sheet as shown in Fig. 22. The discs or suckers 27 are secured to sleeves 69 slidably arranged in thimbles 70 screwing into recesses 71 formed in the periphery of the drum and having ports 72 opening into the interior of the drum; within the drum is arranged a box 73 in which is maintained a vacuum as described in connection with the construction shown in Figs. 20 and 21. As in the rotation of the drum a line of ports 72 are brought into communication with the box 73, the discs will be caused to adhere to the top sheet and the sleeves 69 with their suckers will move radially lifting the front end of the top sheet. After the suckers engage the sheet the latter will move along with the sucker. The path of movement of the sucker when in engagement with the sheet is indicated by dotted line α . When the suckers have reached points at which the sheet should be released the ports pass beyond the box and the sleeves and suckers will be pushed out to their normal positions by springs 74.

It will be understood that the improved feeding mechanism as shown and described as feeding sheets to tin pots, such mechanism can be employed in feeding sheets generally and while advantage is taken of the necessity of maintaining the sheets when being fed to a tin pot to ensure a vacuum within the cups, the passing of the cups through a liquid as they are brought into contact with a sheet is not necessary as air would be forced from the cups by compressing the same when their edges are in contact with the sheet.

As hereinbefore stated the pile of sheets are drawn up against the discs 25 by the balance weight 11 and the pressure thus exerted will present certain resistance to the sliding of the top sheet by the drum. By increasing the pressure, this resistance can be made sufficient to overcome the normal tension of the springs 37 and the drum will be moved to the left, increasing the tension of the springs 37 to a point where such tension will be greater than the friction between the top sheet and the next adjacent sheet of the pile, whereupon the drum will be pulled to right carrying the top sheet with it. During the swing of the drum to the left as above described, the front end of the top sheet will be lifted against the guide fingers.

From the foregoing it will be clear that by suitably adjusting the pressure against the rolls 25 relative to the tension of the springs 37, the swinging of the drum, whereby the front end of the sheet will be raised prior to longitudinal movement of the sheet, can be effected without the employment of the head 30. When employing the head 30, the latter forms a stop to prevent the ad-

vance of the sheet until its front end is raised. By adjusting the pressure on the rolls 25 the sheets are engaged at a point ahead of the drum and held from longitudinal movement until the front end is raised. 70

We claim herein as our invention:

1. A sheet feeding machine having in combination a support, a rotatable and laterally moving drum provided with a plurality of devices adapted to engage the first 75 or outer sheet of a pile resting on the support, an abutment for preventing edgewise movement of the outer sheet of the pile when in normal position on the pile and yielding means for holding the drum in normal position laterally. 80

2. A sheet feeding machine having in combination a rotatable drum provided with a plurality of sheet-engaging devices arranged in vertical rows, a plurality of vertically and longitudinally movable guide fingers extending in between adjacent rows of the sheet-engaging devices, said fingers being adapted to force a sheet from engagement with the sheet-engaging devices at a 90 predetermined point in the paths of movement of such devices. 85

3. A sheet feeding machine having in combination a rotatable drum provided with a plurality of suckers whereby sheets may be 95 raised and moved edgewise, a support for a pile of sheets located below the drum, an abutment for determining the position of the pile of sheets on the support and so arranged with reference to the orbits of the 100 suckers on the drum that the latter will engage the sheets short distances from the abutment.

4. A sheet feeding machine having in combination a tank, means for supplying water to the tank, a support for a pile of sheets arranged in said tank, a rotatable drum provided with a plurality of suckers, the drum being so arranged with reference to the tank that the suckers will be immersed in the water contained in the tank as they are moved into engagement with the first or outer sheet of the pile, and means for moving the support upwardly after a sheet has been withdrawn from the pile. 110

5. A sheet feeding machine having in combination a tank, means for supplying water to the tank, a support for a pile of sheets arranged in said tank, a rotatable drum provided with a plurality of suckers, 120 the drum being so arranged with reference to the tank that the suckers will be immersed in the water contained in the tank as they are moved into engagement with the first or outer sheet of the pile, and means for moving the support upwardly after a sheet has been withdrawn from the pile, and means for maintaining a predetermined level of water in the tank. 125

6. A sheet feeding machine having in 130

- combination a tank or support for a pile of sheets arranged in the tank, a rotatable drum provided with a plurality of suckers and so located with reference to the tank 5 that the suckers will be immersed in the water in the tank as they are moved into engagement with the top sheet of the pile, means for moving the support upwardly after a sheet has been withdrawn from the 10 pile and nozzle so located as to direct streams of water under pressure against the front side of the pile of sheets and means for maintaining a predetermined level of water in the tank.
- 15 7. In a sheet feeding machine, a rotatable drum provided with a plurality of cups or suckers formed of flexible resilient material adapted to be flattened when forced into contact with the sheet and means for permitting a slow continuous flow of air into the 20 cups or suckers.
8. A sheet feeding machine, having in combination a support for a pile of sheets, an abutment for determining the position of 25 a pile of sheets on the support, a rotatable drum provided with a plurality of devices adapted to engage the first or outer sheet of the pile, bearing boxes for the journals of the drum movable relative to the abutment, 30 and means permitting the movement of said boxes and returning the same to normal position.
9. A sheet feeding machine having in combination a support for a pile of sheets, an 35 abutment for determining the position of the front of the pile, means for engaging the top sheet of the pile adjacent to the abutment, and means for moving said engaging means in the arc of a circle, said abut- 40 ment extending beyond the outer sheet of the pile during the removal of the outer sheet from the pile.
10. A sheet feeding machine having in combination a support for a pile of sheets, 45 an abutment for determining the position of the front of the pile, means for engaging the top sheet of the pile adjacent to the abutment, means for moving said engaging means to remove the top sheet from the pile, 50 said abutment extending beyond the outer sheet of the pile during the removal of the outer sheet from the pile, and means for moving the sheet-engaging face of the abutment in the plane of the top sheet.
11. A sheet feeding machine having in combination a support for a pile of sheets, an abutment against which the edges of the sheets bear, said abutment extending beyond the outer face of the pile during the removal of the outer sheet from the pile, means for 60 engaging the top sheet of the pile and moving its abutment-bearing edge beyond the abutment, and means for moving the sheet-engaging face of the abutment in the plane of the top sheet during the removal of the 65 top sheet from the pile.
12. A sheet feeding machine having in combination a support for a pile of sheets, a cylindrical abutment against which the edges of the sheets bear and which has its 70 axis substantially perpendicular to the planes of the sheets, said abutment extending beyond the outer face of the pile during the removal of the outer sheet from the pile, means for engaging the top sheet of the pile 75 and moving its abutment-bearing edge beyond the abutment, and means for rotating said abutment during the removal of the top sheet from the pile.
13. A sheet feeding machine having in 80 combination a support for a pile of sheets, an abutment against which the edges of the sheets bear, said abutment extending beyond the outer face of the pile during the removal of the outer sheet from the pile, means for 85 engaging the top sheet of the pile, means for moving said sheet-engaging means in the arc of a circle, and means for moving the sheet-engaging face of the abutment in the plane of the top sheet during the removal of 90 the top sheet from the pile.
14. A sheet feeding machine having in combination a support for a pile of sheets, a cylindrical abutment against which the edges of the sheets bear and which has its 95 axis substantially perpendicular to the planes of the sheets, said abutment extending beyond the outer face of the pile during the removal of the outer sheet from the pile, means for engaging the top sheet of the 100 pile, means for moving the said sheet-engaging means in the arc of a circle, and means for rotating said abutment during the removal of the top sheet from the pile.

In testimony whereof, we have hereunto 105 set our hands.

SAMUEL E. DIESCHER.
AUGUST P. DIESCHER.
